UNITED STATES PATENT OFFICE.

THOMAS J. COSTER AND DANIEL G. PUTNAM, OF CHICAGO, ILLINOIS.

DEHYDRATING MACHINE FOR DESICCATING LIQUIDS.

1,258,988.

Specification of Letters Patent. Patented Mar. 12, 1918.

Application filed February 2, 1917. Serial No. 146,144.

To all whom it may concern:

Be it known that we, THOMAS J. COSTER and DANIEL G. PUTNAM, citizens of the United States, all residing at Chicago, in the county of Cook and State of Illinois, have invented certain new and useful Improvements in Dehydrating Machines for Desiccating Liquids, of which the following is a specification.

10 Our invention relates to improvements in dehydrating machines for desiccating food products and especially liquids, such as milk, or the like.

One of the objects of our invention is to 15 provide a machine whereby to remove the moisture from milk and other similar liquids or semi-liquids by application of heat, without subjecting the moisture laden liquid, or the products therefrom, to the gases arising 20 from combustion of the fuel employed to produce the heat.

Another object of our invention is to increase the operative efficiency of such machines by utilizing the heat energy contained 25 in the gases after they have passed through the machine, by returning them to the original source of heat to be again passed through the machine.

And still another object of our invention 30 is to regulate the generating effect of the heat-producing furnace by varying the proportionate quantities of the heated gases and fresh air admitted to the furnace.

Other, further and more specific objects 35 of our invention will become readily apparent, to persons skilled in the art, from a consideration of the following description when taken in conjunction with the drawings, wherein

40 Figure 1 is a side elevation of the machine.

Fig. 2 is an enlarged end elevation showing parts in section, taken on line 2—2 of Fig. 3.

45 Fig. 3 is a vertical axial section taken on line 3—3 of Fig. 2.

In all the views the same reference characters are employed to indicate similar parts.

In the embodiment of the accompanying 50 exemplification 5 is a substantially air-tight casing supported upon brackets 6 and 7, on the floor 8. The bottom and top portions of the casing are hopper like, as at 9 and 10,

each terminating in a pipe 11 and 12, respectively. One fixed wall 13 of the casing is 55 disk formed, and is provided on its perimeter with surfaces 14 for a ball bearing and is supported upon and may be a part of the standard 15. Another standard 16 is spaced-apart from the standard 15. The two standards support the stationary shaft 17, which is fixed to the standard 16 by a set screw 18, or otherwise. A drum 20 is rotatable within the casing 5, and is provided with a relatively stiff wall or disk member 21 that terminates axially in a bearing 22 rotatable upon the fixed shaft 17. The peripheral wall 23 of the drum 20 is connected to the disk or radial wall 21, and to another similar, but ring shaped radial wall 25. The ring 70 wall 25 is provided with a ball bearing outwardly-extending annular member 26 that is supported upon the member 14 of the disk 13 with intermediate balls 27. A drive wheel 28 is secured to the outwardly extending 75 hub of the bearing 22 and by this means the inner drum 20 may be rotated upon the shaft 17 and the ball bearing 27. The outer casing 5 may be made in two parts, the upper and lower part, each provided with a 80 flange and connected together by bolts, as at 30, in order that the drum 20 may conveniently be placed within the casing 5.

A conveyer 31 passes through the stationary disk 13 of the outer casing and into the 85 inner drum 20, immediately above the shaft 17. The bottom wall 32 of the conveyer, is supported upon the stationary shaft 17, as by means of rings 33 and 34. That portion of the conveyer extending outside of the 90 drum is inclosed in a casing 36. The conveyer shaft is supported upon a standard 37 and rotated by a pulley 38, supplied from a source of power not shown. The outer end of the casing 36 is connected to a reservoir 39, by a short vertical pipe 40. A scraper 41 extends radially from the conveyer 31 and substantially from the bottom wall 32 into contact with the inner surface 95 of the circumferential wall 23 of the drum 100 20, as at 42. It is held firmly against the inner surface of the rotating drum by a spring 43 or in any other suitable manner for maintaining it in proper contact therewith. The spring 43 may be secured to the 105 stationary shaft 17 and the rotation of the

shaft 17 will vary the tension of the spring 43. A pipe 44 extends into the rotatable drum 20, and through the stationary wall 13 of the outer casing 5, having its other end connected to an air pump 45 for exhausting air vapors and moisture from the interior of the rotating drum 20. The means for operating the pump 45 may be supplied by any well known source of power. The 10 reservoir casing 39 terminates at its bottom end in a hopper like wall 46 to which a pipe 47 is connected. A damper, or valve 48, is included within the pipe to shut off the casing 39 from another similar casing or 15 reservoir 49. The reservoir 49 is connected by a pipe 50 to a disintegrator 52 supplied with power from the shaft 53 through the train of miter gears 54. Another valve or damper 55 is placed in the pipe 50 to shut off the reservoir 49 from the disintegrator. 20 A discharge pipe 56 leads from the disintegrator to communicate with any receptacle in which the finished products are to be deposited.

25 Connected to the lower end of the pipe 11 is a furnace 57, for burning a suitable or appropriate fuel to provide the desired heat. The products of combustion pass from the furnace 57 through the pipe 11, and into 30 the casing 5, around the rotatable drum 20, thus heating the peripheral surface or wall 23 of the drum, after which they find their exit through the pipe 12, beyond the damper 58, when the damper is in open position to permit their exit, or back through the pipe 59 and through the fan 60 to the 35 furnace 57 and preferably below the grate that is contained in the furnace for the support of the fuel, when the damper 58 is closed or partly closed. A damper 61 provides means for admitting a greater or 40 less quantity of fresh air into the pipe 59 and a damper 62 restricts the passage of the air and gases coming from the fan 60, into the furnace. When the dampers 58 and 61 are open, a smaller quantity of the 45 products of combustion are passed back into the furnace and through the casing 5 and when these dampers are closed a greater 50 quantity of the preheated products of combustion will be returned by the same means.

55 The liquid to be desiccated is passed into the interior of the rotatable drum 20, through the pipe 70, which passes through the stationary disk or wall 13, and extends to practically the central portion of the drum where it branches, as at 71, to provide another laterally extending branch 72. Each of these branches is provided with a 60 nozzle 73 and 74, respectively, which are directed toward the peripheral wall 23 of the drum 20. The milk or other material to be desiccated is pumped with some pres-

sure through the pipe 70 and sprayed by the nozzles 73 and 74 into contact with the inner surface of the heated wall 23 of the rotating drum. As the drum is rotating in the direction of the arrow, shown in Fig. 2, the scraper 41 will scrape the deposited solid matter from the milk, from the wall 23, and after being liberated it will pass down the angularly inclined wall of the scraper into the conveyer 31 from whence it will be conveyed into the reservoir 39. The moisture, liberated by the milk striking the hot wall of the rotating drum 23, is pumped from the drum through the pipe 44, and the capacity of the pump is such as to tend to maintain a vacuum in the drum, the effect of which contributes toward the deposit of the solid matters of the liquid upon the hot surfaces of the drum.

When the reservoir 39 is being filled the damper or valve 48, is closed, and when it is desired to remove the material deposited in the reservoir 39, the valve 55 is closed and the valve 48 is opened, thereby permitting the material to pass from the reservoir 39 into the reservoir 49 without breaking the seal and destroying the vacuum effect in the rotating drum. The disintegrator pulverizes or comminutes the flaky deposits into a sufficiently fine powder.

While we have herein shown a single embodiment of our invention, for the purpose of clear disclosure, it is manifest that many changes in general form, arrangement and configuration of the parts may be made within the spirit and scope of the appended claims.

Having described our invention, what we claim is:

1. A machine of the character described comprising a stationary cylindrical casing, means to supply heated gas to the interior of the casing, a rotatable shaft passing therethrough, a drum within the casing and secured at one end to the shaft, a stationary disk at the other end, an annular ring carried at the disk end of the drum and journaled on the disk, a fluid feed pipe passing through the disk for coating the interior of the drum with a fluid to be dried, a scraper carried by the disk for coöperation with the inner wall of the drum, and a conveyer carried by the disk for coöperation with the scraper to remove the dried material to the exterior of the casing.

2. A machine of the character described comprising a stationary cylindrical casing, means to supply heated gas to the interior of the casing, a rotatable shaft passing therethrough, a drum within the casing and secured at one end to the shaft, a stationary disk at the other end, a bearing in said disk for one end of the shaft, an annular ring

carried at the disk end of the drum and journaled on the disk, a fluid feed pipe passing through the disk for coating the interior of the drum with a fluid to be dried,
5 a scraper carried by the disk for coöperation with the inner wall of the drum, and a conveyer carried by the disk and coöper-

ating with the scraper to remove the dried material through the exterior of the casing.

In testimony whereof we hereunto set our ¹⁰ hands.

THOMAS J. COSTER.
DANIEL G. PUTNAM.
